UNITED STATES PATENT OFFICE.

JOHN P. MONGAN, OF MINNEAPOLIS, MINNESOTA.

AUTOMATIC UNCOUPLER FOR CAR-COUPPLINGS.

1,102,941.

Specification of Letters Patent.

Patented July 7, 1914.

Application filed December 13, 1913. Serial No. 306,438.

To all whom it may concern:

Be it known that I, JOHN P. MONGAN, a citizen of the United States, residing at Minneapolis, in the county of Hennepin and 5 State of Minnesota, have invented certain new and useful Improvements in Automatic Uncouplers for Car-Couplers; and I do hereby declare the following to be a full, clear, and exact description of the invention, such 10 as will enable others skilled in the art to which it appertains to make and use the same.

My invention has for its object to provide an automatic uncoupler for car couplers; 15 and, to this end, it consists of the novel devices and combinations of devices hereinafter described and defined in the claims.

In the accompanying drawings, which 20 illustrate the invention, like characters indicate like parts throughout the several views.

Referring to the drawings:—Figure 1 is a view in side elevation, showing the invention applied in working position to a car and car coupler, some parts being broken 25 away, some parts being sectioned, and still other parts indicated in different positions by means of dotted lines; Fig. 2 is an end elevation of the same; and Fig. 3 is a plan view of the coupler, some parts being broken 30 away.

The numeral 1 indicates a car equipped with a coupler 3 of the Master Car Builders' type. The coupler 3 is shown in a locked position, and its knuckle and lock dog are 35 indicated, respectively, by the numerals 4 and 5.

Journalized in a pair of bearings 6, secured to one end of the car 1, is a horizontally extended rock shaft 7, having at its outer end 40 a hand lever extension 8 which works past the outside of the car 1. At its inner end, the rock shaft 7 is provided with a laterally extended crank arm 9, the free end of which terminates directly above the lock dog 5.

Pivotedly attached to the free end of the 45 crank arm 9 is a depending headed plunger 10, which works in a vertically extended tubular casing 11, pivotally attached, at its lower end, to the lock dog 5. A coiled spring 12 is 50 mounted on the plunger 10 within the casing 11, and is arranged to be compressed between the head of said plunger and the free end of said casing 11.

A pawl and ratchet device is provided for 55 locking the rock shaft 7 in a position to place

the spring 12 under tension, as indicated by dotted lines in Fig. 1. The pawl 13 is pivotally attached to a bearing 14 secured to the car 1, and the ratchet 15, which is segmental in form, is rigidly secured to the rock shaft 70 co 7 adjacent to the outer bearing 6.

In uncoupling cars, the hand lever 8 is turned into a dotted line position, as shown in Fig. 1. If the tail of the knuckle 4 is out of frictional engagement with the lock dog 5, said lock dog will be lifted into an inoperative position, to permit the knuckle 4 to swing on its pivot, when the uncoupled cars are separated. In case the tail of the knuckle 4 frictionally engages and holds the 70 dog 5, the spring 12 will be placed under tension, when the lever 8 is turned into its dotted line position. Said spring is held under tension by turning the pawl 13 from its full line position into engagement with the 75 pawl 15, as indicated by dotted lines in Fig. 1. A bumping action of the cars will release the lock dog 5 from frictional engagement with the tail of the knuckle 4, and the spring 12 will automatically lift said lock 80 dog out of engagement with the tail of the knuckle 4, thus permitting the uncoupling of the cars. To release the pawl 13 from the ratchet 15, and thereby permit the lock dog 5 to return to a normal position, I provide a 85 flexible connection 16 between the pawl 13 and the knuckle 4 of the coupler. One end of this connection is permanently secured to the knuckle 4 by a crank arm 17 rigidly secured to said knuckle, and the other or free 90 end thereof is provided with a pin 18, adapted to be seated in a perforated lug 19 on the pawl 13. This lug 19 is so arranged as to hold the pin 18 seated therein when the pawl 13 is turned into engagement with the 95 ratchet 15, but the pin will draw out of the said lug when the pawl 13 drops into an inoperative position, and under the movement of the knuckle 4 when the cars are uncoupled.

In the safety lock dog lifting devices now in use, it is necessary for the train-men, in case the draft strain on a lock dog is such as to prevent the same from being raised, to signal the engineer to bump the cars, in 100 order that said lock dogs may be released from frictional engagement with the tails of the coupler knuckles. By the use of my invention, the train-men can set all of the frictionally held lock dogs under strain, by plac- 110

ing the spring 12 of each device under tension and then turning the pawl 13 into engagement with the ratchet 15. A single bumping of the cars will release all of the held 5 lock dogs, and the set devices will automatically lift the released lock dogs. At the same time each lock dog is placed under lifting strain, the pin 18 on the adjacent car is placed in the perforated lug 19 of the 10 pawl 13. As the cars are then separated, after the lock dogs are raised, the initial movement of knuckles will draw the pawls 13 out of engagement with the ratchets 15, thus permitting the lock dogs to be returned 15 to normal positions. A further movement of the said knuckles will withdraw the pins 18 from the perforated lugs 19.

It is, of course, understood that each coupler of a car will be provided with one of 20 the improved devices.

From the foregoing description, it is evident that the improved device not only affords a safety lock dog lifting device, but it permits a multiplicity of cars to be un- 25 coupled with a great saving of time.

What I claim is:—

1. The combination with a car coupler of the M. C. B. type, of a lever-equipped rock shaft having a crank arm, a spring connection 30 between the lock dog of said coupler and said crank arm, a pawl and ratchet device, for holding said rock shaft in a position to set said spring connection under tension, to lift said lock dog out of engagement with the tail of the knuckle of 35 said coupler, when the frictional contact between said tail and said dog is removed, and a trip actuated by the movement of the knuckle of said coupler for automatically 40 releasing said pawl from said ratchet, to

permit said lock dog to return to an operative position.

2. The combination with a car coupler of the M. C. B. type, of a lock dog lifting device arranged to be set to automatically lift 45 said lock dog out of engagement with the tail of the knuckle of said coupler, when the frictional contact between said tail and said dog is removed, and a trip actuated by the movement of the knuckle of said coupler, for automatically releasing said lock dog, when in an inoperative position, to permit the same to return to an operative position. 50

3. The combination with a car coupler of the M. C. B. type, of a lever-equipped rock shaft having a crank arm, a spring connection 55 between the lock dog of said coupler and said crank arm, a pawl and ratchet device for holding said rock shaft in a position to set said spring connection under tension, to lift said lock dog out of engagement with the tail of the knuckle of said coupler, when the frictional contact between 60 said tail and said dog is removed, and a flexible connection between the knuckle of said coupler and said pawl, for releasing said pawl from said ratchet, by the opening movement of said knuckle, said flexible connection being of a length sufficient to 65 permit normal movement of said knuckle when said pawl is in an inoperative position. 70

In testimony whereof I affix my signature in presence of two witnesses.

JOHN P. MONGAN.
